Primary Examiner — Eric Goodman*Assistant Examiner* — Daniel J Domino(74) *Attorney, Agent, or Firm* — Design IP(57) **CLAIM**

The ornamental design for an display screen portion with animated graphical user interface, as shown and described.

DESCRIPTION

FIG. 1 is a front view of a first image of an display screen portion with animated graphical user interface showing my new design;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the transitional image sequentially transitions between the images shown in FIGS. 1 through 6. The process or period in which one image transitions to another image forms no part of the claimed design.

The broken line showing of a portion of a display screen in FIGS. 1 through 6 forms no part of the claimed design. The broken line showing of text and portions of the graphical user interface in FIGS. 1 through 6 represents environmental subject matter and forms no part of the claimed design.
